H. P. RAVN.
HOLDING MEANS FOR JARS.
APPLICATION FILED FEB. 20, 1918.

Patented Dec. 17, 1918.

Inventor,
Hans Peter Ravn, by
G. Kennedy,
Attorney.

UNITED STATES PATENT OFFICE.

HANS PETER RAVN, OF WATERLOO, IOWA.

HOLDING MEANS FOR JARS.

1,288,190.

Specification of Letters Patent.

Patented Dec. 17, 1918.

Application filed February 20, 1918. Serial No. 218,834.

To all whom it may concern:

Be it known that I, HANS PETER RAVN, a citizen of the United States of America, and a resident of Waterloo, Blackhawk county, Iowa, have invented certain new and useful Improvements in Holding Means for Jars, of which the following is a specification.

My invention relates to improvements in holding means for jars, operable to adjustably resiliently receive, hold and releasably clamp jars or the like receptacles, especially that type of holding means which are provided with cross handles and are constructed from a single piece of wire. The object of the invention is to provide such a device with means to hold a jar by a clamping action to secure it firmly against displacement, and to support it in spaced relation above a surface on which the device is placed to permit the free circulation of a fluid therebetween, and thus prevent damage to the jar while facilitating handling it. The operating means stated is shown in the accompanying drawing, which is a perspective view of my improved elastic holding and clamping device for jars, and in which a jar is indicated by dotted lines as held inclosed in the device and grasped by its oppositely-located resilient jaws.

My invention is operably formed from a single piece of resilient wire rod, which is suitably bent or shaped to provide supports and resilient clamping jaws for a contained jar. With this end in view, I take a piece of wire rod 1 and shape it into a bail with downwardly directed members of equal length. The rod at the lower end of one of said members is offset slightly to supply a suspending portion 2. The rod at the lower end of the portion 2 is bent horizontally to provide a short horizontal member 3, and then bent again at an angle to furnish another short horizontal member 4, then bent downwardly at 5 to provide a supporting leg, then upwardly at 6, then in a curve horizontally at 7 and then downwardly at 8, the parts 6, 7 and 8 thus providing a resilient jaw whose cross-part 7 is concave inwardly to fit the side of a jar grasped by it when a jar is placed in the device.

The rod 1 at the lower end of the part 8 is bent upwardly to provide a supporting leg 9, then bent horizontally at 10 and again at an angle at 11, then bent upwardly at 12 55 to have its extremity coiled at 13 about the angle of meeting of the opposite rod part 1 and its downwardly directed suspending part 14 which is parallel to the said suspending part 12. The rod at the lower end 60 of the part 14 is bent horizontally at 15 inwardly, then at an angle at 16, then downwardly at 17 to provide another leg, then upwardly, across and downwardly at 18, 19 and 20 to supply another resilient jaw 65 opposite to the said jaws 6, 7 and 8, of like form and dimensions to clamp the opposite side of a jar placed in said device. The rod at the lower end of the jaw part 20 is bent upwardly to provide the leg 21, then 70 horizontally at 22 and then horizontally at an angle at 23 to provide a jar support, then upwardly at 24 to have its other extremity coiled at 25 about the angle of meeting of the rod parts 1 and 2. 75

The device described, has raised supporting parts 10, 11 and 15, 16 on one side, and 3, 4 and 22, 23 at the opposite side in the same horizontal plane, spaced apart, to receive the lower end of the jar 26, where the 80 legs 5, 9, 17 and 21 keep the bottom of the jar a distance above the bottom of a boiler or other surface to permit free circulation of fluid under the jar, and keep the jar away from the heated surface below which 85 might cause damage because of too rapid heat conduction.

The jaws 6, 7, 8 and 18, 19, 20 are placed oppositely so as to firmly resiliently releasably clamp a jar between them, and will 90 expand or contract resiliently to fit different sized jars within their limits, and thus hold the jar safely from displacement or without danger of slopping its contents, if uncovered. The bail is rigid, placed well 95 above the top of the jar, and convenient in use in carrying the jar without swinging, and facilitates placing or removing the jar relative to a container.

Having described my invention, what I 100 claim as new, and desire to secure by Letters Patent, is:

A jar holding device, composed of a single piece of resilient wire forming a central bail and oppositely arranged coacting holding portions, each holding portion comprising a jaw adapted to engage a jar, horizontal jar supports, legs extending downward from said supports, a suspending por-

tion continuous with the bail at one side of the device, and a suspending portion secured at its end to said bail at the opposite side of the device.

Signed at Waterloo, Iowa, this 15th day of Feb. 1918.

HANS PETER RAVN.
